UNITED STATES PATENT OFFICE.

VICTOR H. JENNINGS, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TUBE FRAME FOR AXMINSTER LOOMS.

Application filed December 27, 1923. Serial No. 683,057.

To all whom it may concern:

Be it known that I, VICTOR H. JENNINGS, a citizen of the United States, residing at Worcester, in the county of Worcester and State of Massachusetts, have invented a new and useful Tube Frame for Axminster Looms, of which the following is a specification.

This invention relates to tube frames for 10 Axminster looms, and more particularly to the construction and mounting of the hooked means by which the tube frame is attached to the transporting chain ordinarily found in this type of loom.

15 The principal object of my invention is to provide a loose pivotal connection between the hook and the bracket so formed that the pressure of supporting the tube frame, whether the latter be right side up or inverted, shall be transferred directly from the hook member to the bracket forming members without the use of pins, small shafts, or other fixed pivotal connections.

A further object of my invention is to 25 provide a bracket formed in two members having associated therewith a rigid hook provided with offset portions which shall cooperate with the bracket members so that when in one position one of said members 30 will take the strain of supporting the tube frame and when in an inverted position the other member of the bracket will support the tube frame.

A still further object of the invention is 35 to provide a tube frame constructed with a rigid hook having an offset shouldered portion which shall have a loose pivotal connection with the bracket.

With these and other objects in view, 40 which will appear as the description proceeds, my invention resides in the combination and arrangement of parts hereinafter described and set forth in the claims.

In the drawings, wherein one form of my 45 invention is disclosed,

Fig. 1 shows an end elevation of a tube frame constructed according to my invention,

50 Fig. 2 is a side elevation of the tube frame shown in Fig. 1 but with certain portions shown in vertical section, and

Fig. 3 is a perspective view showing a portion of the hook forming part of my invention.

In the drawings I have shown a hollow 55 metallic tube frame 10 to which are secured in any approved manner the yarn tubes 11 as by means of angle member 12. A spool 13 is provided with a gudgeon 14 to be received by the spool bearing member and may 60 be formed as desired.

In carrying out my invention, I provide a spool bearing member 15, the lower end 16 of which extends into and is secured to the upper part of the tube frame 10 by means 65 of screws 17. The upstanding portion of the spool bearing member is arranged to receive the gudgeon 14 and is also provided with a slot 18 which in the form shown in the drawing, preferably extends to the lower 70 end portion 16.

The chain engaging member 19 is provided with the usual offset 20 and has a leg 21 extending into the tube frame and secured to the lower part thereof by means of screws 75 22 and is also provided with a boss 23 for a purpose to be described. As usually constructed, the chain engaging member 19 is provided with a slot for the reception of a hook and in this instance I extend this slot 80 24, to a point somewhat above the lower end of slot 18 formed in the spool bearing member. The spool bearing and chain engaging members are removably held together 85 by screws 25.

An important feature of my invention relates to the construction of the chain engaging hook and I have shown in the drawings a preferred form which may preferably be made as a drop forging. The hook, shown at 26, is provided with a horizontally extending portion 28 on the under face of which is formed a boss 29 which is preferably located vertically above boss 23. A compression spring 30 is located between the leg 21 and the portion 28 of the hook and is held in place by bosses 23 and 29, the function of the spring being to hold the head of the hook against the offset portion 20 of the chain engaging member.

As shown in Figs. 2 and 3, the body of the hook is provided with an offset portion 31 which defines an upper shoulder 32 and a lower shoulder 33. The offset portion 31 is located in the slots 18 and 24 and is so proportioned as to be slightly less in its vertical dimension than the distance between the upper end of slot 18 and lower end of slot 24.

In assembling this structure, the hook 26 is placed in slot 24 of the chain engaged member with spring 30 in position before being applied to the tube frame. The parts 5 are then moved to the position shown in Fig. 2, the spool bearing member 15 having previously been attached to the tube frame, the upper shoulder 32 lying under the upper end of slot 18. Screws 25 are then 10 passed through the chain engaging member into the spool bearing member. This affords a construction which can be readily assembled or taken apart for repairs.

As shown in Fig. 1 shoulder 32 is in engagement with the member 15 while the shoulder 33 is spaced slightly above the bottom of slot 24. In this way the strain of supporting the tube frame from the chain is transferred from the hook to its upper 20 shoulder and from there to the spool bearing member, the horizontal portion 16 of which extends into the tube frame and transfers the strain to the latter independently of screws 17 or 22. It frequently happens 25 that the tube frame, as it travels through the loom, is in a position inverted from that shown in Fig. 2 and in this position it will be seen that the weight of the tube frame is transferred to the chain by means of the 30 chain engaging member 19, the thrust being taken by leg 21 independently of screws 17 or 22.

Thus it will be seen that I have provided a tube frame construction wherein the chain 35 engaging hook has a loose pivotal connection with the bracket which is afforded by an offset in the hook lying in aligning slots formed in the bracket members, this result being attained without the use of a drilled 40 hole, journals or other forms of fixed bearing. The offset is so proportioned as to move with freedom in the aligning slots of the bracket members so that it will respond readily to the action either of the spring 30 45 or the loom actuated disengaging means usual in the type of loom to which the invention relates but not shown in the drawings.

Having thus described my invention, it 50 will be evident that changes and modifications may be made by those skilled in the art without departing from the spirit and scope of the invention as set forth in the appended claims and I do not wish to be otherwise limited to the details herein disclosed.

What I claim is:

1. In a tube frame for Axminster looms, a bracket having a slot formed therein and extending lengthwise of the tube frame, a 55 hook member associated with the bracket and having an enlarged portion thereof defining upper and lower shoulders and located in

said slot and restrained as to vertical motion by the engagement of said shoulders by the ends of said slot, and resilient means for holding said hook in outward position. 65

2. In a tube frame for Axminster looms, a bracket having an opening therethrough extending longitudinally of the tube frame, a hook member associated with the bracket 70 and having an enlarged portion thereon defining a pair of shoulders positioned for engagement with the bracket at the ends of the slot, and resilient means to hold said hook in outward position. 75

3. In a tube frame for Axminster looms, a spool bearing member having a slot therein, a chain engaging member secured thereto and having a slot therein in alignment with the slot in said spool bearing member, 80 a hook member having shoulders formed thereon intermediate the ends thereof and lying in the aligning portions of said slot, one shoulder positioned for engagement with the spool engaging member and the other shoulder positioned for engagement with the chain engaging member, and yielding means to hold said hook in outward position. 85

4. In a tube frame for Axminster looms, a spool bearing member having a slot formed therein, a chain engaging member having a slot formed therein, portions of 90 said slots being in alignment, a tube frame member to which said bearing and chain engaging members are secured, the lower end of the slot in the outer of the two members being above the tube frame, a hook formed with shoulders for engagement with the spool bearing and chain engaging members and located in the aligning portions of said 100 slot, and yielding means to hold said hook outwardly. 105

5. In a tube frame for Axminster looms, a bracket secured to the tube frame and having an opening therethrough extending longitudinally of the tube frame, a hook member having an offset portion defining shoulders lying in said slot and mounted for limited vertical motion in said slot, and yielding means to hold said hook outwardly. 110

6. In a tube frame for Axminster looms, a bracket formed of two separable parts removably attached to the frame, said parts having openings therethrough, portions of 115 which are in alignment to define a slot through said bracket longitudinally of the frame, a hook member passing through the slot in said bracket and having portions, one to engage each of said parts, to limit vertical motion of said hook, and resilient means to hold said hook outwardly. 120

In testimony whereof I have hereunto affixed my signature.

VICTOR H. JENNINGS.
